G. MURPHY ET AL

NEEDLE LATCH OPENING DEVICE FOR KNITTING MACHINES

Original Filed April 13, 1921

UNITED STATES PATENT OFFICE.

GILBERT MURPHY, OF PHILADELPHIA, PENNSYLVANIA, AND WALTER A. SIMOND, OF FRANKLIN, NEW HAMPSHIRE, ASSIGNORS TO ACME KNITTING MACHINE & NEEDLE COMPANY, OF FRANKLIN, NEW HAMPSHIRE, A CORPORATION OF NEW HAMPSHIRE.

NEEDLE-LATCH-OPENING DEVICE FOR KNITTING MACHINES.

Original application filed April 13, 1921, Serial No. 460,957. Divided and this application filed March 10, 1924. Serial No. 698,006.

To all whom it may concern:

Be it known that we, GILBERT MURPHY and WALTER A. SIMOND, citizens of the United States, residing, respectively, at Philadelphia, in the county of Philadelphia and State of Pennsylvania, and at Franklin, in the county of Merrimack and State of New Hampshire, have invented a new and useful Improvement in Needle-Latch-Opening Devices for Knitting Machines, of which the following is a specification, like reference characters on the drawings indicating like parts in the several figures.

This invention relates to knitting machines, and more especially to circular knitting machines adapted to knit either plain or ribbed work and to change automatically from one style of knitting to the other. The present application is a division of our prior application Serial No. 460,957, filed April 13, 1921.

The application just mentioned shows a hosiery knitting machine adapted to knit automatically a seamless stocking having a fashioned toe and heel and a ribbed leg or ribbed cuff, as may be desired. This machine includes a cylinder supporting a circular series of cylinder needles, a dial holding another series of needles, and suitable cams for operating both sets of needles. The plain knitting operations are performed on the cylinder needles alone, and the dial needles are brought into operation only in knitting ribbed work. Consequently, in knitting a stocking of the character above described, the dial needles are inactive or out of operation during the knitting of a considerable part of the stocking. When these needles are brought into operation to knit a ribbed section of fabric, it is necessary to open the latches of the dial needles in order to be sure that each needle will take thread and properly perform its functions.

The present invention has for its chief object to devise a simple, effective, and reliable means for ensuring the opening of the latches of the needles in a knitting machine. While the invention will be herein disclosed as embodied in the machine shown in our prior application, it will be evident that the invention is not limited in its application to machines of this type.

The nature of the invention will be readily understood from the following description when read in connection with the accompanying drawings, and the novel features will be particularly pointed out in the appended claims.

Referring now to the drawings,

Figure 1 is a view, partly in vertical cross section and partly in side elevation, showing a knitting machine dial and parts adjacent thereto including a latch opening device embodying this invention;

Fig. 2 is a bottom view of the dial cam cap and the dial cams supported thereby;

Fig. 3 is a front elevation of the latch opening magnet;

Figs. 4 and 5 are cross sectional views on the lines 4-4 and 5-5, respectively, Fig. 3;

Fig. 6 is a plan view, partly broken away, of the dial cam cap; and

Fig. 7 is a view similar to Fig. 2 but showing the cams drawn inwardly.

Fig. 1 shows a knitting machine dial 2 supporting a series of dial needles 3, the dial being provided with suitable slots to receive and guide the needles. Mounted immediately above the dial 2 is a dial cam cap 4 carrying a series of cam segments or members which cooperate to form a path 5 for the butts of the dial needles 3. The dial 2 and cap 4 are mounted for relative rotation, the arrangement in the machine shown in our prior application, above designated, including means for holding the dial stationary while the cap 4 and the cams carried thereby revolve. This relative rotation enables the cams to move the needles 3 backward and forward in their grooves to give them the desired knitting movements. In the arrangement shown the cap 4 is rotated in the direction indicated by the arrow in Fig. 2, and the needles are projected by the knitting cam 6, then drawn backwardly by the fixed cam 7 and the stitch cam 8, and are subsequently advanced and withdrawn again by the rear cam 10 to cast off their stitches.

For the purpose of opening the latches of the dial needles when they are first brought into operation after having been inactive for a time, a permanent magnet 12 is secured to the edge of the dial cam cap 4 by means of a screw 14. The edge of the cap is notched,

as shown at 15, Fig. 2, to receive the magnet 12. Preferably this magnet is U-shaped and is supported in an inverted position so that part of the magnet overlies the cap 4 and its rearward end extends down almost to the surface of the cap, as best shown in Fig. 1. The opposite end of the magnet is located immediately above the path of movement of the dial needles, and it has an inclined or 10 cam-shaped face, as best shown in Figs. 3, 4 and 5. This face comprises a leading tip 16 which is located close to the needles in position to attract the latches of the needles and initiate their opening movement, as shown 15 in Fig. 4. The face also includes a receding trailing part 17 which is so shaped that as the magnet travels past the needles, and the needles in the meantime are being advanced radially under the dial cam cap, each needle 20 latch will be attracted by portions of the magnet face which are located at successively increasing distances from the path of movement of the needles. The opening movement of the latch, therefore, is continued 25 by these trailing portions of the magnet, as shown, for example, in Fig. 5. It will be seen from an inspection of Fig. 2 that the magnet 12 is located opposite the knitting cam 6 and in advance (with reference to the 30 direction of rotation) of the high point of the knitting cam. Also that the circumferential extent or width of the magnet is so proportioned with regard to the shape of the cam 6 that the latch will be moved into an 35 upright position before the needle projecting movement is completed. The final forward movement of the needle therefore, will result in completing the opening movement 40 of the latch just before the needle reaches its yarn taking position.

This simple arrangement, therefore, ensures the opening of the needle latches. The use of the U-shaped magnet arranged, as 45 shown, is of advantage in increasing the magnetic flux which flows through the needle latch.

While we have herein shown and described the best embodiment of our invention that we have so far devised, we do not desire to 50 be limited to the exact details of the construction shown.

Having thus described our invention, what we desire to claim as new is:

1. In a knitting machine, the combination 55 of a series of needles, supporting means for

said needles, cams for operating said needles, and a magnet mounted adjacent to the path of movement of said needles and having a face comprising a leading portion located close to said path to act on the ends of the 60 needle latches to initiate their opening movement, and trailing portions located at successively increasing distances from said path and arranged to continue the opening movement of the latches as the magnet is relatively moved past said needles. 65

2. In a circular knitting machine, the combination of a dial, a series of needles supported in said dial, cams for operating said needles, said needles and cams being mounted 70 for relative rotation, and a permanent magnet mounted in a fixed relationship to said cams and opposite the knitting cam to open the latches of the needles while they are being advanced by said 75 knitting cam to receive the thread or yarn, said magnet having an inclined face including a leading portion located closely adjacent to the path of travel of the ends of the needle hooks and a receding trailing 80 portion, whereby as the magnet is relatively moved past each needle the latch of the needle is attracted by portions of the magnet located at successively increasing 85 distances from the body of the needle. 85

3. In a circular knitting machine, the combination of a dial, a series of needles supported in said dial, cams for operating said needles, a dial cam cap for supporting said cams, said cams and dial being supported 90 for relative rotation, a U-shaped permanent magnet mounted on the edge of said dial cam cap and having a face located close to the path of movement of the needles and another part extending backwardly to 95 a point closely adjacent to said cap, the face of said magnet being inclined and including a leading part located close to said path in a position to initiate the opening movement of said latches and a receding trailing part 100 shaped to cause portions thereof located at successively increasing distances from said path to attract the latch of each needle and continue its opening movement as the magnet and needle are relatively moved one past 105 the other.

In testimony whereof we have signed our names to this specification.

GILBERT MURPHY.
WALTER A. SIMOND.
